SEWING MACHINE

Curt Wilhelm Schweiger, Munich, Germany

Application April 4, 1934, Serial No. 718,907
In Germany May 4, 1933

2 Claims. (Cl. 112—158)

This invention relates to a drive for the regulatable transverse motion of the needle bar in zigzag sewing machines, in which lateral motion is imparted to the needle bar by a link non-detachably disposed between the needle bar bearing and a driving lever oscillating about a fulcrum.

In known machines of this kind the end of the link articulated to the swinging driving lever is adjustable in a slot or the like of the driving lever from the fulcrum in order to change the extent of the transversal stroke of the needle bar, so that the removal of the end of the link from the fulcrum of the driving lever will result in an enlargement of the stitching width. When the end of the link is disposed in the fulcrum of the swinging driving lever, a transverse displacement of the needle bar does not take place and the machine is then adjusted for the lock stitch.

This known drive arrangement suffers from the drawback that it is practically impossible to provide for accurate adjustment of the machine to lock stitch position. Apart from the fact that the accurate fixing of the link in the fulcrum of the driving lever requires special attention and care, the accuracy of adjustment is necessarily affected by the unavoidable wear of the adjusting device which consists of numerous small parts. As a matter of experience, machines of this type, even if used only a relatively short time, will disclose a slight tendency of the needle bar to oscillate transversely when adjusted for the lock stitch. For this reason, clean back-stitching work cannot be done for any length of time if the known driving arrangement for needle bars is employed.

It has been proposed already to eliminate completely the connection between the link and the laterally swinging driving means during the sewing of the straight seam and to place the released end of the link on a special bolt on the casing of the sewing machine. The known devices of this kind are, however, open to the objection that the connecting screws between the link and the driving means have to be unscrewed in a bothersome manner and the lifted end of the link must then be placed on the stationary bolt of the casing of the machine and secured thereto. Furthermore, such arrangements can be used only if both the link and the swinging driving means are located outside the sewing machine casing so as to be accessible from the outside.

According to the invention, the drawbacks mentioned are eliminated by causing the needle bar bearing or the link to become automatically disengaged from the laterally swinging driving means

when the regulating member controlling the extent of motion of the needle bar is in zero position, and to remain locked to the casing of the machine without requiring complete disconnection of the link and the driving means. For this purpose, in the example shown in the drawing, the link is articulated to one end of the oscillatory driving lever so as to be immovable on the latter, and the pivot of the oscillatory driving lever is formed by a special bolt displaceable and fixable in a slot of the machine casing and capable of varying its position on the lever relative to the fulcrum for adjusting the extent of oscillation of the needle bar. This bolt engages with a pin thereof a longitudinal slot, which is open at the joint of the link, of the oscillatory lever having a forked top end and being driven by a cam disc. When the pin at the fulcrum is passed out of the slot of the oscillatory lever, it enters a groove arranged on the link vertically to the direction of sliding and thus prevents lateral displacement of the link by the driving lever freely swinging about the link pin. Absolutely exact adjustment of the machine to the lock stitch position is therefore insured without effort and without special attention and loss of time.

The same effect can be attained also by other means, and the invention is not limited to the arrangement described below but resides in the automatic abolishment of the effective connection of the oscillatory drive with the needle bar and in the automatic simultaneous locking of the needle bar bearing or link during displacement of the adjusting members for the extent of oscillation of the needle bar into zero position, i. e. when the machine is adjusted to lockstitching or trimming.

By way of example, the invention is illustrated in the accompanying drawing, in which

Fig. 1 is a view, partly in section, of the driving means,

Fig. 2 a top view thereof, partly in section,

Fig. 3 a vertical section on the line A—B of Fig. 2, and

Fig. 4 is a view of part of the sewing machine casing with the adjusting device for the width of the stitches.

Referring to the drawing, the main shaft *a* drives by means of the helical gears *b* or other suitable means a cam disc *c* which engages the forked end of the oscillatory lever *d* and imparts thereto a reciprocating motion. To the other end of the lever *d* the link *e* is articulated in a forked manner by means of the bolt screw *f*. The oscillatory lever *d* has a longitudinal slot *g*

- which is open at the joint or axis of the bolt *f* and extends there into a groove *h* of the link *e* disposed vertically to the direction of displacement. In the grooves *g*, *h* slides with a suitable pin the bolt *i*, which by means of guide faces and a slide *k* can be displaced in a slot *m* of the machine casing *n*. A tension spring *o* and knurled nut *p* serve for clamping the bolt *i* and slide *k* at the desired point in the slot *m*. The accurate adjustment of the bolt *i* is facilitated by a scale on the slot *m* and a mark on the slide *k*.
- The link *e* guided in a bearing *q* is connected at its free end by a suitable recess with the needle bar casing *r* or the needle bar guide *s*, the recess being formed so that during axial displacement of the link *e* an arc-like oscillation of the needle bar *t* about an axis *u* is insured which lies in the extension of the axis of a ring looper horizontally moved in front of the needle bar.
- To avoid interference with the oscillation of the lever *d* at the jointing point with the link *e*, suitable play is provided at the joint of the grooves *g*, *h* and the faces of the oscillatory lever *d* and link *e*, which are opposite to one another here, are preferably outwardly rounded or chamfered.

What I claim, is:

1. A drive for the regulatable transverse motion of the needle bar in zigzag sewing machines, comprising a bearing for the needle bar, a driving lever having a displaceable fulcrum constructed as a bolt for varying the range of motion of the needle bar, a link non-detachably disposed between said bearing and driving lever for imparting lateral motion to said needle bar and articulated to said driving lever, and means for automatically disengaging the bolt from said driving lever to render the latter ineffective and for locking the link and needle bar against lateral motion when said bolt is displaced into zero position.
2. A drive according to claim 1, in which the bolt is displaceable and fixable in a slot in the sewing machine casing and fitted with a pin engaging a longitudinal slot of the driving lever, said latter slot being open at the joint, said bolt passing out of the latter slot during adjustment of the machine for straight stitching and into a groove of the link disposed vertically to the direction of displacement thereof.

CURT WILHELM SCHWEIGER.
